UNITED STATES PATENT OFFICE.

ROLLAND F. SHERFY, OF WASHINGTON, DISTRICT OF COLUMBIA.

DISPENSING CABINET.

Application filed February 25, 1927. Serial No. 170,936.

This invention relates to a dispensing cabinet, and has for its primary object a construction by means of which tubes of paste or other semi-solid material may be housed for sanitary reasons to assume positions such that the contents may be readily dispensed upon the manipulation of a compressing means.

An object of the invention is the provision of a cabinet in which the various parts are so designed and arranged that the cabinet will not only be capable of dispensing material but will support a mirror in position to be utilized in conjunction with the use of the material dispensed from the cabinet.

Another feature of the invention is the novel design and association of the various elements entering into the construction of the cabinet so that the cost of manufacture is materially reduced and the cost of assembling also reduced to a minimum, thereby enabling me to place the cabinet upon the market at a relatively low cost.

With these and other objects in view, my invention will be better understood from the accompanying drawings, wherein:

Figure 1 is a perspective view of the cabinet;

Figure 2 is a vertical front to rear sectional view on the line 2—2 of Figure 3;

Figure 3 is a vertical transverse sectional view;

Figure 4 is a sectional view on the line 4—4 of Figure 3;

Figure 5 is an enlarged sectional view of the upper portion of the cabinet;

Figure 6 is an enlarged cross sectional view showing the means for rotating the shafts by which the tubes are supported;

Figure 7 is a sectional view on the line 7—7 of Figure 6;

Figure 8 is a perspective view of one end portion of one of the tube supporting shafts;

Figure 9 is a perspective view of the closure for the tube spout;

Figure 10 is a perspective view of the key plate;

Figure 11 is a detail plan view of the closure for the tube spout;

Figure 12 is a detailed sectional view of a modified construction for closing the end of the shaft.

Again referring to the drawings illustrating one of the many embodiments of my invention, the numeral 1 designates a casing of any suitable configuration but shown in this

particular instance as of rectangular formation having portions of the side walls 2 depressed, as indicated at 3, to provide bearings 4 and semi-spherical recesses 5. The spool construction provided for winding and squeezing the tube 7 is shown as consisting of a pair of aligned hollow shafts 8 and 9, having their abutting ends mounted in a central bearing 9^b.

To materially reduce the cost of manufacture, the shaft is formed from tubing and is provided with a slot 10 through which is inserted the usual flat, sealed end 11 of the tube so as to assume the position, as illustrated at 12, to facilitate the winding of the tube about 70 the shaft in the dispensing of the contents of the tube.

Mounted upon the rear wall of the casing at the inner side thereof, and opposite each of the shafts 8 and 9, is a combined abutment 75 and displacing member for the tube supported by the respective shaft, the said member comprising a plate 13 of resilient metal, one end of which plate is secured as at 14 to the said rear wall of the casing, the other end of 80 the plate, indicated by the numeral 15, resting in engagement with the inner side of the said rear wall of the casing, the plate between its ends being formed to provide forwardly converging upper and lower portions 13^a and 13^b, and an intermediate portion 13^c which is substantially parallel to the plane of the said rear wall of the casing, the abutment member being rounded at the juncture of its lower portion 13^a and its intermediate portion 13^c, 90 as indicated by the numeral 17, and this portion being located in rear of and somewhat lower than the under side of the respective shaft 8 as clearly shown in Figure 5 of the drawings, it being observed by reference to 95 said figure that when either shaft 8 or 9 is rotated to wind the respective tube 7 thereon, the tube will be compressed or constricted as it is drawn between the said shaft and the intermediate portion 13^c of the abutment member, this compression of the tube serving to effect discharge of a portion of the contents of the tube through the spout thereof. It will likewise be understood that, due to the relative disposition of the rounded portion 17 of 100 the member 13 and the shaft 8 or 9, the respective tube 7 will be swung outwardly or forwardly, as the shaft 8 or 9 is rotated to wind the tube thereon, thus automatically presenting

the discharge spout of the tube at the 110

front of the cabinet and consequently in a position where the tooth paste may be readily removed as it is discharged from the spout. It will also be observed by reference to Figure 5 that the intermediate portion 13^e of the member 13 is located relatively close to the rear side of the respective shaft 8 or 9, so as to effect compression of the tube 7 as the tube is wound about the shaft 8 or 9 and drawn 10 between the said shaft and the respective member 13, and due to the fact that the members 13 are of resilient metal the said members 13 will yield sufficiently to permit of passage of the collapsed portions of the respective tubes 7 therebetween and the respective shaft 8 or 9, and at the same time exert sufficient pressure against the respective tubes 7 to insure of a complete displacement of the contents of the tubes from between the walls 20 of the tubes as the tubes are collapsed.

Another important feature of my invention resides in novel means whereby each shaft 8 or 9 may be independently rotated. This construction in one of its forms as illustrated in 25 the figures of the drawings consists of a key plate 18 provided with notches 19 interfitting or interlocking with portions of the shaft when this plate is arranged in notches 20 formed in the end of the respective shaft. 30 Thus it will be appreciated that this key plate has an interlocking engagement with the end of the shaft and projects a predetermined distance at right angles beyond the shaft so that the same may be gripped for rotating 35 the shaft.

For the purpose of preventing displacement of this key plate out of its interlocking engagement with the shaft, I provide a novel construction of cap 21 comprising the disk 22, and the split cylindrical body 23 which projects from one side of the disk and is yieldably forced into the tube so that the disk may have abutting relation with the key plate to prevent dislocation of the latter. To increase the effective grip of the cap with the shaft and to further prevent accidental displacement of the shaft in the bearings 4, I provide a finger 24 constituting a longitudinal extension of the body of the cap and bearing 45 against the inner surface of the shaft in parallel and opposed relation to a tongue 25 which also bears against the inner surface of the shaft and has a projection 26 projecting through the slot 10 so as to have abutting relation with the inner surface of the respective bearing and thus the cap performs the triple function of securing the key plate against displacement, closing the end of the shaft, and restraining the shaft against axial movement 50 55 60 relative to the bearing.

In Figure 12, I have illustrated a somewhat simpler construction for accomplishing this desired result, and as illustrated consists of a disk 27 provided with openings 28 for the reception of overturned lugs 29 carried

by the end of the shaft 30. It will be appreciated that when the key plate 31 is arranged in its interlocking engagement with the shaft as heretofore set forth, bending of the tongues over the disk effectively locks the disk, key 70 and shaft together as a unit.

To complete my invention, I provide a novel construction of closure 32 consisting of the clamp 33 and the cut-off 34. The clamp construction 33 is illustrated as comprising 75 a pair of jaws 35 pivotally connected together and to the cut-off 34, by a pivot pin 36, and movable toward and away from each other by the adjusting screw 37 to bring about effective engagement of the jaws with the neck 38 80 of the tube 7.

From the foregoing description taken in connection with the accompanying drawings, it will be appreciated that I provide a cabinet of unique construction in which any number of paste tubes may be suspended in position to be readily accessible, and by the simple manipulation of a key at the side of the cabinet the required amount of paste may be dispensed from the tube. Immediately upon 90 completion of this operation, the door 39 may be closed to allow a person to utilize the mirror 40 carried by the door.

The particular feature of my invention is the simplicity of construction and the rigid connection of the various parts so that displacement of the parts in the operation thereof is prevented. Of course, it will be understood that the various parts may be designed and associated in other relations than 95 illustrated, as the main feature of my invention is to simplify the construction as a whole without in any manner sacrificing the advantages thereof and, therefore, I do not desire to be limited in any manner except as 100 set forth in the accompanying claims.

I claim:

1. In an apparatus for dispensing paste from collapsible tubes, a casing, a shaft rotatably mounted therein and embodying means for anchoring the sealed flat end of a tube thereto, means operable to rotate the shaft to wind the tube thereon, and an abutment located in spaced relation to the shaft and having a rounded portion located in rear of and below the said shaft for engagement by the rear side of the tube which is anchored to the shaft, whereby rotation of the shaft will effect winding of the tube thereon and compression of the tube between the shaft and the abutment, the rounded portion of the abutment constituting means for forwardly swinging the tube as the tube is drawn up by the shaft.

2. In an apparatus for dispensing paste from collapsible tubes, a casing, a shaft rotatably mounted therein and embodying means for anchoring the sealed flat end of a tube thereto, means operable to rotate the shaft to wind the tube thereon, and an abutment

- comprising a resilient plate having one end secured to that wall of the casing which is opposite the said shaft, the abutment having portions converging in the direction of the 5 shaft and an intermediate portion extending between the converging portions, the said intermediate portion and the lower converging portion being merged on a curved line in rear of and below the lower side of the shaft 10 to constitute an abutment for the tube as the tube is wound upon the shaft and effect forward swinging displacement of the tube and, simultaneously, a compression of the tube between the intermediate portion of the abutment and the said shaft to effect ejection of 15 the contents of the tube.
3. In an apparatus for dispensing paste from collapsible tubes, a casing, a shaft rotatably mounted therein and embodying 20 means for anchoring the sealed flat end of a tube thereto, means operable to rotate the shaft to wind the tube thereon, and an abutment comprising a resilient plate having one end secured to that wall of the casing which 25 is opposite the said shaft, the abutment having portions converging in the direction of the shaft and an intermediate portion extending between the converging portions, the said intermediate portion and the lower converging portion being merged on a curved 30 line in rear of and below the lower side of the shaft to constitute an abutment for the tube as the tube is wound upon the shaft and effect forward swinging displacement of the tube 35 and, simultaneously, a compression of the tube between the intermediate portion of the abutment and the said shaft to effect ejection of the contents of the tube, the lower portion of the said abutment member having its rear 40 end resting in engagement with the said wall of the casing.
4. In an apparatus for dispensing paste from collapsible tubes, a casing, a bearing within the casing intermediate opposite side walls thereof, inwardly projecting recessed bearings upon the said side walls of the casing, shafts journaled at their outer ends in the said bearings of the side walls of the casing and at their inner ends in the first mentioned bearing, means upon the outer end of each shaft and housed within the bearing, for rotating the shafts independently of each other, each shaft embodying means for anchoring the sealed flat end of a tube thereto, 45 and an abutment located opposite each shaft for engagement by the tube to effect compression of the tube in the rotation of the respective shaft.
5. In an apparatus for dispensing paste 50 from collapsible tubes, a casing, bearings upon the opposite side walls of the casing, a bearing within the casing between the first mentioned bearings, shafts mounted at their outer ends in the first mentioned bearings and rotatably mounted at their inner ends in the 55 last mentioned bearing, means associated with the outer end of each shaft whereby the same may be rotated, each shaft embodying means for anchoring a sealed flat end of a tube thereto, and an abutment located in 60 spaced relation to each shaft and between which and the said shaft the respective tube is to be drawn in the rotation of the said respective shaft and whereby to effect compression of the tube and delivery of the contents 65 thereof.
6. In apparatus of the class described, a casing, a hollow shaft journaled in the casing and having one end projecting exteriorly of the casing, a key disposed diametrically of the said end of the shaft, and a cap having a hollow body fitted to the said end of the shaft and provided with notches accommodating the key, the said cap constituting means for holding the key assembled with the shaft. 70
7. In apparatus of the class described, a casing, a hollow shaft journaled in the casing and embodying means for anchoring the sealed flat end of a tube thereto, the shaft having one end projecting exteriorly of the casing, the said end of the shaft having oppositely located notches therein, a key disposed diametrically of the said end of the shaft and seating in said notches, and a cap having a hollow body fitted to the said end of the shaft and maintaining the key in assembled position within the notches in the shaft. 75
8. In apparatus of the class described, a casing, a hollow shaft journaled in the casing and embodying means for anchoring the sealed flat end of a tube thereto, the shaft having one end projecting exteriorly of the casing, the said end of the shaft having oppositely located notches therein, a key disposed diametrically of the said end of the shaft and seating in said notches, a cap having a hollow body fitted to the said end of the shaft and maintaining the key in assembled position within the notches in the shaft, 80 and means upon the body of the cap for coaction with the said shaft to hold the cap against displacement with respect to the shaft. 85
9. In apparatus of the class described, a casing, a hollow shaft journaled in the casing and embodying means for anchoring the sealed flat end of a tube thereto, the shaft having one end projecting exteriorly of the casing, the said end of the shaft having oppositely located notches formed therein, a key disposed diametrically of the said end of the shaft and seating in said notches, a cap having a hollow body fitted to the said end of the shaft and provided with notches registering with the first mentioned notches and engaging the said key, the shaft having an opening therein, and a locking tongue extending longitudinally from the body of the cap and provided with a projection hav- 90

ing locking engagement in said opening whereby to retain the cap assembled with the end of the shaft.

10. In apparatus of the class described, a
5 casing having a bearing in one wall thereof, a hollow shaft journaled in the bearing and embodying means for anchoring the sealed flat end of a tube thereto, the shaft having one end projecting exteriorly of the casing
10 and beyond the bearing, the said end of the shaft having oppositely located notches formed therein, a key disposed diametrically of the said end of the shaft and seating in said notches, a cap having a hollow body fitted

to the said end of the shaft and provided with 15 notches registering with the first mentioned notches and engaging the said key, the shaft having an opening therein, and a locking tongue extending longitudinally from the body of the cap and provided with a projection 20 having locking engagement in said opening whereby to retain the cap assembled with the end of the shaft, the said projection engaging the bearing interiorly of the casing to restrain the shaft against outward displacement.

In testimony whereof I affix my signature.
ROLLAND F. SHERFY.
